US00D487284S

(12) **United States Design Patent** (10) Patent No.: **US D487,284 S**
(45) Date of Patent: ** Mar. 2, 2004

(54) **EYEGLASSES**(75) Inventor: **Henry Welling Lane**, San Luis Obispo, CA (US)(73) Assignee: **Dioptics Medical Products, Inc.**, San Luis Obispo, CA (US)(**) Term: **14 Years**(21) Appl. No.: **29/182,369**(22) Filed: **May 22, 2003**(51) LOC (7) Cl. .... **16-06**(52) U.S. Cl. **D16/326; D16/321; D16/337**

(58) Field of Search D16/101, 300-330, D16/335-340, 900; D29/109, 110; D24/110.2; 351/41, 44, 51, 52, 57-61, 111, 121, 123, 153, 156-158; 2/426, 428, 430, 436, 444, 448, 449

(57) **CLAIM**

The ornamental design for eyeglasses, as shown and described.

DESCRIPTION

FIG. 1 is a top perspective view of eyeglasses showing my new design;

FIG. 2 is a front elevation view of eyeglasses thereof;

FIG. 3 is a rear elevation view of eyeglasses thereof;

FIG. 4 is a left side elevation view of eyeglasses thereof, the right side being a mirror image of the left side;

FIG. 5 is a top view of eyeglasses thereof; and,

FIG. 6 is a bottom view of eyeglasses thereof.
